UNITED STATES PATENT OFFICE

JAMES M. NAUL, OF PLAINFIELD, NEW JERSEY, ASSIGNOR TO THE SINGER MANUFACTURING COMPANY, OF ELIZABETH, NEW JERSEY, A CORPORATION OF NEW JERSEY

ELECTRIC SUCTION CLEANER

Application filed August 15, 1929. Serial No. 386,165.

This invention relates to vacuum or suction cleaners of the portable electric motor-driven type having a motor, a fan, a cleaning nozzle and a dirt-receptacle, which are 5 mounted to move together as a unit over the surface to be cleaned.

The invention has for an object to provide such a device with a simple, efficient and inexpensive means of speed-control to 10 better adapt the cleaner to the particular carpet, rug or surface to be cleaned. For example, in cleaning light weight rugs, a lower vacuum-cleaner speed is deemed preferable than when cleaning heavier rugs, it 15 being desirable to run the vacuum cleaner at a speed such that the particular rug being cleaned will not stick to the cleaner nozzle and thus be dragged over the floor.

A further object of the invention is to provide for the speed-control of a suction cleaner without encumbering the outfit with unsightly enlargements, protuberances or heat generating devices.

Still further, the invention has for an 25 object to provide a speed-controlled suction cleaner which is easy to operate and in which the starting and stopping means and the speed-controlling means are closely associated for convenience of operation, but are 30 separated in such a way as to be unlikely to confuse the operator.

To the attainment of the ends in view, the motor of the device, which is preferably 35 of the series commutator type, is provided with a tapped field-winding, the taps of which are extended into the hollow handle of the device, together with the main motor leads. One leg of the current-supply cord is connected through a single-pole single- 40 throw on-and-off switch to one of the motor leads. The motor-field taps are connected to the points of a selector-switch, the movable contact element of which is connected to the other leg of the current-supply cord. 45 The "on-and-off" switch is preferably mounted upon a plate provided with an inlet aperture and spring guard for the current-supply cord; such plate being mounted at the under side of the vacuum cleaner handle near the 50 upper or free end of the latter; the pivoted

handle of the switch projecting outwardly from the handle alongside the current-supply cord and hence readily associated with the cord in the mind of the operator as the switch-handle for turning the electric current on or off. The selector-switch is preferably mounted on a separate plate secured to the vacuum cleaner handle near the free end of the latter but on the upper or opposite side of the handle from the "on-and-off" 60 switch. The selector or speed-control switch is thus readily accessible for convenient operation, yet is so separated from the "on-and-off" switch as to be naturally readily distinguished from the latter. 65

In the accompanying drawings, Fig. 1 is a side elevation of a suction cleaner embodying the invention. Fig. 2 is a diagram of the wiring of the device. Fig. 3 is a longitudinal vertical section through the handle of the device. Fig. 4 is a longitudinal section through the lower end of the handle, showing the plug-connection between the motor leads and the conductors within the handle. Fig. 5 is a perspective view of the 70 female member of the connector. Fig. 6 is a perspective view of the male member of the connector. Fig. 7 is an end view of the connector-member shown in Fig. 5. Fig. 8 is a bottom plan view of the selector-switch shown at the left in Fig. 3, and Fig. 9 is a top-plan view of the "on-and-off" 75 switch shown at the right in Fig. 3.

In the preferred embodiment of the invention illustrated, 1 represents the fan-casing or body of a suction cleaner having a cleaning nozzle 2 and carrying an electric motor 3 direct connected as usual to a fan 3' within the casing 1. The usual dirt-receptacle 4 hangs from the hook 5 on the switch-plate 6 and is connected to the air-discharge tube 7 leading from the casing 1. 85

The motor is preferably of the series commutator type having an armature M and field f connected in series with the main 90 motor leads 8, 9. The field winding f is tapped between its ends and the tap 10 is included with the leads 8 and 9 in the cable 11 which extends from the motor 3 to a male member 12 of a three-pin plug-connector 100

which is received by the mating member 13 fitted into and closing the lower end of the hollow tube 14 constituting the handle of the suction cleaner.

5 Screwed to the under side of the handle 14 over the slot 15 near the upper end of the handle is the switch plate 6 previously referred to. This plate is formed with an inlet aperture 16 for the current-supply cord 17 which is protected by the usual spring wire guard 18. Screwed to the switch-plate 6 and disposed within the slot 15 in the handle-tube 14 is a single-pole single-throw toggle-switch 19 of standard 10 construction. The switch shown has a pivoted operating handle 20 and a movable bridging contact member 21 which in its "on" position connects the stationary contact 22 to a similar contact 22' at the other 15 side of the switch, thereby connecting one leg of the current-supply cord to the main motor-lead 8. Secured over the slot 23 in the upper side of the handle is a switch-plate 24 on which is mounted a standard single-pole double-throw toggle-switch 25 serving 20 as a selector-switch to connect the other leg of the current-supply cord 17 to one or the other of the field connections 9, 10.

The switch 25 comprises a pivoted switch-lever 26, a bridging contact member 27, a pair of contacts 28, 29 on one side of the switch, and a pair of similar contacts 28', 29' similarly disposed at the other side of the switch, all supported in insulated relation. One current-supply wire 17 is connected to the two under side contacts 28', 29'. The field terminal lead 9 is connected to the contact 28, and the field-tap 10 is connected to the contact 29. With the 30 switch-lever in the up position shown in Fig. 3, the current supply wire 17 is connected to the field-tap 10 and the motor will run at its higher speed. When the switch-lever 26 is thrown down to the position shown in Fig. 1, the motor will run at its lower speed. Manipulation of the switch-lever 20 will start and stop the motor regardless of the setting of the speed-control switch-lever 26.

40 Both switch-levers 20, 26 are simultaneously accessible to one of the operator's hands and, being on different sides of the handle 14, are easily distinguished from one another. The operator learns naturally that the "on-and-off" switch is the one closely associated with the current-supply cord.

The motor is preferably so wound and its brushes so set as to have universal characteristics, that is, to run at substantially 50 the same speeds on either direct or alternating current of a given voltage.

Having thus set forth the nature of the invention, what I claim herein is:

60 1. In a suction cleaner, the combination with a fan-casing and nozzle, of an elec-

tric motor having a main current-supply lead and a plurality of speed-control leads, a hollow tubular handle connected to said fan-casing and through which said leads extend, a plurality of separate switches disposed within said handle, and a current-supply cord leading into said handle, one of said switches being an "on-and-off" switch connected in one of the current-supply legs and the other switch being a selector-switch connected to the speed-control leads from the motor.

70 2. In a suction cleaner, the combination with a fan-casing and nozzle, of an electric motor having a main current-supply lead and a plurality of speed-control leads, a hollow tubular handle connected to said fan-casing and through which said leads extend, a plurality of separate switches disposed within said handle and having operating means exteriorly disposed at different sides of said handle, and a current-supply cord leading into said handle, one of said switches being an "on-and-off" switch connected in one of the current-supply legs and the other switch being a selector-switch connected to the speed-control leads from the motor.

80 3. A suction cleaner having an electric motor with a plurality of speed-control leads, a hollow handle for propelling said cleaner, said handle having slots in its upper and under sides adjacent its free end, a switch-plate covering the under slot in said handle and formed with an inlet aperture for the current-supply cord, an "on-and-off" switch connected to said motor and mounted on said switch-plate and disposed in said under slot, a second switch-plate covering the upper slot in said handle, and a selector-switch mounted on said second switch-plate and disposed in said upper slot and connected to the motor speed-control leads.

90 4. A suction cleaner having a casing including a cleaner nozzle, an electric motor mounted on said casing and having a tapped field winding, a handle for propelling the cleaner casing and nozzle, a switch mounted on said handle and connected to said tapped field winding to vary the effective turns of the latter, and a second switch mounted on said handle and connected to said motor to start and stop the latter.

100 In testimony whereof, I have signed my name to this specification.

110 JAMES M. NAUL.
